DESIGN FOR AN ASH TRAY

William E. Powers, Dayton, Ohio

Application March 16, 1943, Serial No. 109,766

Term of patent 3½ years

To all whom it may concern:

Be it known that I, William E. Powers, a citizen of the United States, residing at Dayton, in the county of Montgomery and State of Ohio, have invented a new, original, and ornamental Design for an Ash Tray, of which the following is a specification; reference being had to the accompanying drawing, forming a part thereof.

Figure 1 is a perspective view of an ash tray, showing my new design;

Figure 2 is a top plan view thereof; and
Figure 3 is a side elevational view of the same.

I claim:

The ornamental design for an ash tray, as shown.

WILLIAM E. POWERS.
